UNITED STATES PATENT OFFICE.

JULIAN M. STRICKLAND, OF PORT REPUBLIC, NEW JERSEY.

HOLDER FOR FIBROUS LUBRICANT-APPLICATORS.

1,047,852.

Specification of Letters Patent. Patented Dec. 17, 1912.

Application filed August 23, 1911. Serial No. 645,534.

To all whom it may concern:

Be it known that I, JULIAN M. STRICKLAND, a citizen of the United States, residing at Port Republic, in the county of Atlantic and State of New Jersey, have invented new and useful Improvements in Holders for Fibrous Lubricant-Applicators, of which the following is a specification.

This invention relates to holding means for sustaining a fibrous lubricant applicator in a trough provided upon the spout of an oil can, and the primary object of the invention is to provide a simple and effective device of this character comprising a single element which is so arranged with relation to the trough as to be effectively locked upon the trough as well as to be readily removable from the trough.

With the above object in view, and others which will be more apparent as the nature of the invention progresses, the improvement resides in the novel construction and arrangement of parts hereinafter fully described and claimed.

In the drawings, accompanying this specification, Figure 1 is a side elevation of my improvement showing the same in an applied position upon an oil can. Fig. 2 is a central longitudinal sectional view of the same.

In the drawings, the numeral 1 designates an ordinary oil can. These cans, as is well known, are provided with a flexible bottom and have their top formed with a projecting threaded cover which is generally integrally constructed with the can.

The threaded collar designated by the numeral 2 of the oil can is in the present instance adapted to receive the threaded end 3 of a spout 4 comprising parts of the improvement. The spout 4, directly above the threaded end 3, is formed with an annular flange 5 which has its ends inturned and extended downwardly, and the said inturned portion is adapted to receive a suitable washer 6, constructed of leather, rubber or other suitable compressible material, and which is adapted to tightly close the joint between the spout and the collar 2 of the can 1.

The spout 4, disposed from its connection with the flange 5 and secured to the free extremity of the said flange, is a substantially rectangular trough 7. This trough projects a suitable distance beyond each of the opposite faces of the flange, and the said trough

is adapted to serve as a receptacle for the oil delivered from the can 1. The opposite transverse edges of the rectangular trough 7 are each provided with suitable openings, 60 the latter alining, and the said openings are adapted to receive a suitable locking rod designated by the numeral 8. This lock is preferably constructed of a strand of wire, and has one of its ends bent downwardly 65 and inwardly so that the off-set portion thereof resiliently contacts with the under face of the inclined trough 7 adjacent one of the ends thereof. This off-set portion, designated by the numeral 9, is adapted to 70 exert a pressure upon the bottom of the inclined trough so as to sustain the locking rod in a proper position therein. The rod 8 is adapted to pierce a fibrous material 10 which is arranged within the trough. This 75 material 10 is adapted to serve as a brush or dauber whereby the lubricant is applied to the different surfaces of machinery to be oiled. The material comprising the member 10 is preferably formed from a 80 sponge, waste, or other suitable porous material and by arranging the rod as above described it will be noted that the said member 10 may be readily removed from the inclined trough 7 when desired and a new 85 member 10 may be supplanted. It will be noted that by the peculiar construction of the locking member 8 the angular part thereof, which engages one of the ends of the trough serves as a finger hold whereby 90 the said locking member may be withdrawn from the trough and again inserted through the trough to provide for the adjustment of the member 10 with relation to the bottom of the trough. Furthermore it 95 will be understood that the finger 9 of the said member, which is adapted to exert a tension toward the main arm of the lock automatically sustains the lock in its position with relation to the trough without danger 100 of the accidental withdrawal of the lock from the trough.

By arranging the trough 7 at an inclination to the spout 4, as clearly shown in the figures of the drawings, it will be noted that the operator grasping the can need not contort the muscles of his wrist when applying the lubricant to surfaces arranged at different angles, and from the above description, taken in connection with the accompanying drawings, the simplicity of the device, as well as the advantages thereof will, it is 110

thought, be perfectly apparent to those skilled in the art to which such inventions appertain without further description.

Having thus fully described the said invention, what I claim is:—

In a holder for a fibrous applicator, the combination with a substantially rectangular trough having its ends provided with openings, the said trough adapted to receive a fibrous applicator which is adapted to project through the open mouth thereof, of a locking member for the applicator, said member comprising a strand of resilient wire, one of the ends of which being downturned and being provided with a longi-

tudinally extending portion arranged in a plane directly below and adapted to exert a pressure toward the upper arm provided by the wire, the upper and longer arm adapted to pass through the openings in the trough and through the applicator, and the lower arm adapted to be engaged beneath the under face of the trough and adapted to exert a tension thereon.

In testimony whereof I affix my signature in presence of two witnesses.

JULIAN M. STRICKLAND.
